BELT FOR PERSONAL WEAR

Filed June 9, 1932

Inventor
Morris Sachs,

By Attorney

UNITED STATES PATENT OFFICE

MORRIS SACHS, OF ROCHESTER, NEW YORK, ASSIGNOR TO HICKOK MANUFACTURING COMPANY, INC., OF ROCHESTER, NEW YORK, A CORPORATION OF NEW YORK

DESIGN FOR A BELT FOR PERSONAL WEAR

Application filed June 9, 1932. Serial No. 44,035. Term of patent 3½ years.

To all whom it may concern:

Be it known that I, MORRIS SACHS, a citizen of the United States, residing at Rochester, in the county of Monroe, and State of New York, have invented a new, original, and ornamental Design for a Belt for Personal Wear, of which the following is a specification, reference being had to the accompanying drawing, forming part thereof.

The salient features of the design reside in a plaited belt strap of contrasting colors comprising a relatively wide central strip of one color, and narrow interlaced inner and outer side strips of a contrasting color, the outer side strips forming marginal loops and straight transverse portions. The marginal loops are linked into one another and the straight transverse portions cross the inner side strips, alternately, at the front and rear faces of the inner side strips and are alternately arranged at the front and back of the relatively wide central strip. The front

transverse portions are substantially parallel and at approximately right angles to the side edges of the central strip. The transverse portions at the back of the central strip are inclined with relation to the side edges of the central strip.

In the drawing:—

Figure 1 is a plan view of my new design looking at the front of the belt, the end portions being shown in broken lines.

Fig. 2 is an enlarged fragmentary plan view looking at the outer side of the belt.

Fig. 3 is an enlarged fragmentary view of the inner side of the belt.

Fig. 4 is a fragmentary edge view of the belt; and

Fig. 5 is a transverse sectional view through said belt.

I claim:

The ornamental design for a belt for personal wear as shown and described.

MORRIS SACHS.
